BAKERY TRAY OR THE LIKE

Lewis T. Johnson, Bartlesville, Okla., assignor to Phillips
Petroleum Company, Bartlesville, Okla.

Filed Jan. 17, 1974, Ser. No. 434,005

Term of patent 14 years

Int. Cl. D3—02

U.S. Cl. D87—1 R

FIG. 2

FIG. 3

FIG. 4

FIG. 5

FIG. 9

FIG. 10

FIG. 8

FIG. 7

FIG. 6

FIG. 11

FIG. 1 is a top perspective view of a bakery tray or the like showing my new design;

FIG. 2 is a top plan view;

FIG. 3 is an end elevational view;

FIG. 4 is an elevational view of one side;

FIG. 5 is an elevational view of the other side;

FIG. 6 is a sectional view taken on the line 6—6 of FIG. 3;

FIGS. 7, 8, and 9 are sectional views taken on the lines 7—7, 8—8, and 9—9, respectively, of FIG. 4;

FIG. 10 is an enlarged elevational view of the lower right hand corner of FIG. 5; and

FIG. 11 is a partial perspective view showing a modified form of my new design wherein the only modification is the provision of ledges on the inner surfaces of the

inclined bar members which comprise the walls of the tray.

I claim:

The ornamental design for a bakery tray or the like, as shown and described.
